UNITED STATES PATENT OFFICE.

OTTO LIEBKNECHT, OF FRANKFORT-ON-THE-MAIN, GERMANY, ASSIGNOR TO THE
REOSSLER & HASSLACHER CHEMICAL CO., OF NEW YORK, N. Y., A CORPORATION
OF NEW YORK.

ELECTROLYTIC PROCESS OF MAKING ALKALI PERBORATES.

1,235,905.

Specification of Letters Patent.

Patented Aug. 7, 1917.

No Drawing.

Application filed January 6, 1916. Serial No. 70,592.

To all whom it may concern:

Be it known that I, OTTO LIEBKNECHT, a subject of the Emperor of Germany, residing at Frankfort-on-the-Main, Germany, have 5 invented certain new and useful Improvements in Electrolytic Processes of Making Alkali Perborates, of which the following is a specification.

This process relates to the art of making 10 perborates and it particularly relates to a process for the electrolytic production of sodium perborate by an electrolytic process.

It is known that alkali perborates may be obtained by double decomposition of alkali 15 percarbonates with alkali borates; it is also known that alkali percarbonates may be produced by the electrolysis of alkali carbonates.

It has therefore been a problem of technical 20 importance to investigate whether or not it would be possible to produce percarbonates electrolytically in an economical way and to simultaneously cause them to react with borates, thereby producing perborates. The

success of such an enterprise would seem to 25 be discouraged by the many difficulties met in the effort to substantiate the proposition. If for instance an alkali carbonate solution is electrolyzed, the yield, though satisfactory at the beginning, falls in relatively short time to zero. The same phenomenon occurs when electrolyzing an alkali carbonate solution containing also borax; furthermore in this electrolytic process there is a 30 point where just as much active oxygen is generated in the form of percarbonate as is reduced at the cathode, *i. e.* there is an equilibrium in the process.

Therefore it appeared to be rather hopeless to attempt to obtain perborates by such a process as a double decomposition between an electrolytically generated percarbonate and the borates. I have discovered, however, and made the surprising observation that it is possible to produce, for instance sodium perborate, in an economical way if the electrolysis is carried out in the presence of solid sodium perborate, *i. e.* if sodium perborate is present in the solid phase. It is 45 immaterial for the success of the process in which way the solid sodium perborate enters the solution. The sodium perborate may

be generated spontaneously during the electrolysis of a solution containing soda and borax, or it may be generated by cooling the 55 temperature of the electrolyte relatively a short time after electrolysis has started so that at least part of the generated perborate is thereby precipitated, but I find it more suitable to add solid perborate soon after 60 the electrolysis has started or to add immediately from the beginning so much perborate to the solution that sodium perborate is present in solid form, *i. e.* in the solid phase.

By this step I succeed by further electrolysis in transforming the greater part of the borax contained in the electrolyte in the form of a solid, crystalline sodium perborate. It is most surprising that the sodium perborate so formed is no more reduced at 70 the cathode.

But in this process also the yield is found to decrease continuously. The cause of this phenomenon was found to reside in the solution being impoverished of borax. This 75 disadvantage may be counteracted by adding to the solution either continuously or at suitable intervals, preferably while stirring the same, as much borax as is transformed in the form of perborate, thus continuously 80 replenishing the borax whereby a highly saturated solution of borax is obtained. By carrying out the process in this way I succeed in transforming great quantities of borax into sodium perborate, by one operation.

I find it advantageous in this process to apply the raw material practically free from catalysts, though I may render harmless any catalyst which might happen to be in 90 the solution, by adding for instance a negative catalyst, as for instance stannic acid or magnesium silicate.

It is especially advantageous to add one or several substances serving as accelerating 95 agents and exerting a favorable influence on the reaction to the electrolyte, as for instance alkali bicarbonates or materials generating the same. The substances mentioned above also seem to exert their influence in the 100 same direction.

When I am using both in the specification and the claims the expressions: "solid alkali perborate, an excess of an alkali perborate,

- solid sodium perborate," I do mean: alkali perborate or sodium perborate in the solid phase.
- I claim:
5. 1. The process of making alkali perborate, consisting in a double decomposition of a solution of electrolytically produced alkali percarbonate with a solution of an alkali borate in the presence of a solid alkali perborate. 70
  10. 2. The process of making alkali perborates, consisting in electrolyzing a solution of an alkali carbonate and an alkali borate in the presence of a solid alkali perborate. 75
  15. 3. The process of making alkali perborates, consisting in electrolyzing a solution of an alkali carbonate and alkali borate and adding a solid alkali perborate after the beginning of the electrolysis. 80
  20. 4. The process of making alkali perborates, consisting in electrolyzing a solution of alkali carbonate and alkali borate and cooling the electrolyte a short time after electrolysis has started to precipitate part of the generated alkali perborate. 85
  25. 5. The process of making alkali perborates, consisting in providing an excess of an alkali perborate in a solution of an alkali carbonate and an alkali borate, and electrolyzing the solution thus treated. 90
  30. 6. The process of making alkali perborates, consisting in electrolyzing a solution of an alkali carbonate and an alkali borate in the presence of a solid alkali perborate and replenishing the borax in the proportion the generated alkali perborate is precipitated. 95
  35. 7. The process of making alkali perborates, consisting in electrolyzing a solution of an alkali carbonate and an alkali borate free from catalytic agents in the presence of a solid alkali perborate. 100
  40. 8. The process of making alkali perborates, consisting in substantially freeing a solution of an alkali carbonate and an alkali borate from catalytic agents by adding a substance rendering harmless the catalytic agents and electrolyzing the solution thus purified in the presence of a solid alkali perborate. 105
  45. 9. The process of making alkali perborates, consisting in substantially freeing a solution of an alkali carbonate and an alkali borate from catalytic agents by adding a negative catalyst and electrolyzing the solution thus purified in the presence of a solid alkali perborate. 110
  50. 10. The process of making alkali perborates, consisting in preparing a solution of alkali carbonate and alkali borate previously freed from catalytic agents and electrolyzing said solution in the presence of a solid alkali perborate. 115
  55. 11. The process of making alkali perborates, consisting in electrolyzing a solution of an alkali carbonate and alkali borate in the presence of a solid alkali perborate and adding to the solution a substance serving as an accelerating agent. 120
  60. 12. The process of making alkali perborates, consisting in electrolyzing a solution of an alkali carbonate and an alkali borate in the presence of a solid alkali perborate and adding to the solution an alkali bicarbonate serving as an accelerating agent. 125
  65. 13. The process of making alkali perborates, consisting in electrolyzing a solution of an alkali carbonate and an alkali borate in the presence of a solid perborate and adding to the solution sodium bicarbonate serving as an accelerating agent. 130
  70. 14. The process of making alkali perborates, consisting in electrolyzing a solution of an alkali carbonate and an alkali borate free from catalytic agents, in the presence of a solid alkali perborate and adding sodium bicarbonate as an accelerating agent. 135
  75. 15. The process of making sodium perborate, consisting in electrolyzing a solution of sodium carbonate and borax in the presence of solid perborate. 140
  80. 16. The process of making sodium perborate, consisting in electrolyzing a solution of sodium carbonate, and adding solid sodium perborate after the beginning of the electrolysis. 145
  85. 17. The process of making sodium perborate, consisting in electrolyzing a solution of sodium carbonate, and borax in the presence of solid sodium perborate and cooling the electrolyte a short time after electrolysis has started. 150
  90. 18. The process of making sodium perborate, consisting in providing an excess of sodium perborate in a solution of sodium carbonate and borax, and electrolyzing the solution thus treated. 155
  95. 19. The process of making sodium perborate, consisting in electrolyzing a solution of sodium carbonate and borax in the presence of solid sodium perborate and replenishing the borax in the proportion the generated sodium perborate is formed. 160
  100. 20. The process of making sodium perborate, consisting in electrolyzing a solution of sodium carbonate and borax free from catalytic agents in the presence of solid sodium perborate. 165
  105. 21. The process of making sodium perborate, consisting in substantially freeing a solution of sodium carbonate and borax from catalytic agents by adding a substance rendering harmless the catalytic agents and electrolyzing the solution thus purified in the presence of solid sodium perborate. 170
  110. 22. The process of making sodium perborate, consisting in substantially freeing a solution of sodium carbonate and borax from catalytic agents by adding a negative catalyst and electrolyzing the solution thus 175

purified in the presence of solid sodium perborate.

23. The process of making sodium perborates, consisting in preparing a solution of sodium carbonate and borax previously freed from catalytic agents and electrolyzing said solution in the presence of solid sodium perborate.

24. The process of making sodium perborates, consisting in electrolyzing a solution of sodium carbonate and borax in the presence of solid sodium perborate and adding to the solution a substance serving as an accelerating agent.

15 25. The process of making sodium perborates, consisting in electrolyzing a solution of sodium carbonate and borax in the pres-

ence of solid sodium perborate and adding to the solution sodium bicarbonate serving as an accelerating agent.

26. The process of making sodium perborates, consisting in electrolyzing a solution of sodium carbonate and borax free from catalytic agents, in the presence of solid sodium perborate and adding sodium bicarbonate as an accelerating agent.

In testimony whereof I have signed this specification in the presence of two subscribing witnesses.

OTTO LIEBKNECHT.
